ABSTRACT

A laminated container has an outer box with an intermediate liner and an inner liner. A tear strip extends around the outer box for separating an upper portion of the outer box from a lower portion of the outer box. A lower portion of the intermediate liner is glued to the lower portion of the outer box while the intermediate and inner liners are glued together.

11 Claims, 4 Drawing Figures

LAMINATED CONTAINER

BACKGROUND OF THE INVENTION

1. Field of the invention

The invention relates to laminated containers and, in particular, to corrugated paperboard or cardboard containers for shipping and storing quantities of bulk flowable material, such as polyethylene pellets.

2. Description of the prior art

The prior art, as exemplified in U.S. Pat. Nos. 2,048,123, 2,275,896, 3,014,630, 3,134,531, 3,291,372, 3,726,467 and 3,744,702, includes many laminated containers constructed of corrugated paperboard or cardboard designed to contain various materials including bulk flowable material. Many of the prior art corrugated paperboard containers are incapable of containing relatively large quantities of flowable bulk material since they do not have sufficient strength in the side walls and corners to withstand the force or pressure exerted by the flowable material. Also, several of the prior art containers when opened have flaps which interfere with removal of the material and which are not readily reclosable to store unused portions of material in the container. Other prior art containers have liners with tab panels forming overlapping joints resulting in additional sharp corners which tend to interfere with removal of bulk material as well as the replacement of telescoping tops.

SUMMARY OF THE INVENTION

The invention is summarized in that a laminated container comprises an outer box having five serially hinged side panels, a bottom, and a top, one of said outer box side panels being on one end of the series of outer box side panels for overlapping the outer box side panel on the other end of the series of outer box side panels to form a joint, said outer box side panels having a tear strip extending longitudinally along the series of outer box side panels a predetermined distance below the top for separating a top portion of the outer box from a lower portion of the outer box; an intermediate liner; and an inner liner; one of said intermediate liner and said inner liner having four serially hinged panels, the ends of the series of one liner panels capable of forming an abutting corner joint; the other of said intermediate liner and said inner liner having five serially hinged panels, the end panels of the series of other liner panels having a combined size corresponding to a respective one of the panels of said one liner panel for forming an abutting side joint; said outer box side panels, said intermediate liner panels, and said inner liner panels forming respective plies of the sides of the container with the inner liner panels being glued to respective intermediate liner panels and with lower portions of the intermediate liner panels being glued to the respective lower portions of the outer box side panels.

An object of the invention is to construct a container having improved strength at side walls as well as at corners joining the side walls.

Another object of the invention is to provide a container with a removable top which can be readily slipped over a liner portion of the container to reclose the container.

One advantage of the invention is that a novel construction for a liner in a container forms a smooth inside wall surface for allowing complete and easy removal of a material within the container as well as

forming a smooth outer wall surface for allowing the removal and replacement of a telescoping top to the container.

One additional feature of the invention is the provision of a pair of tabs in an outer side panel joined to respective oppositely extending tear strip portions, one of the tear strip portions extending in an overlapping panel of a manufacturer's joint for providing a strong manufacturer's joint and allowing the tear strip to be torn in the direction of the overlapping panel.

BRIEF DESCRIPTION OF THE DRAWINGS

FIG. 1 is a perspective view with portions broken away of a laminated container in accordance with the invention.

FIG. 2 is a perspective view taken at an angle extending from the bottom of the container shown in FIG. 1.

FIG. 3 is a cross section view of a portion of the container shown in FIG. 1 taken along lines 3-3.

FIG. 4 is a plan cross sectional view of a modified laminated container in accordance with the invention.

DESCRIPTION OF THE PREFERRED EMBODIMENTS

As illustrated in FIG. 1, a laminated container in accordance with the invention includes an outer box having side walls formed from five serially hinged panels 10, 12, 14, 16 and 18 wherein the panel 18 is secured, for example, by glue to the panel 10 in an overlapping relationship to form a joint. Flaps 20, 22, 24 and 26 are hinged on the upper edges of the respective panels 10, 12, 14 and 16 to be folded and secured together in a conventional manner to form a top for the container. As shown in FIG. 2, a bellows-type bottom for the container has a rectangular panel 28, a triangular panel 30, a rectangular panel 32, a triangular panel 34 and a rectangular panel 36 hinged at the bottom edges of the respective side panels 10, 12, 14, 16 and 18. A fold panel 40 is hinged at score line 42 to the panel 28 and at score line 44 to the panel 30; a fold panel 46 is hinged at score line 48 to the panel 30 and at score line 50 to the panel 32; a fold panel 52 is hinged at score line 54 to the panel 32 and at score line 56 to panel 34; and a fold panel 58 is hinged at score line 60 to the panel 34 and at score line 62 to the panel 36. The bellows bottom is designed to be folded as shown, and the adjoining edges of the panels 28 and 33 and the panels 12 and 16 are designed to be taped together to seal the bottom to prevent leakage of material from the bottom.

An intermediate liner of the container includes four serially hinged panels 68, 70, 72 and 74. The panels 74 and 68 on the ends of the series of intermediate liner panels form an abutting joint in the same corner where the overlapping panel 18 forms a joint with the panel 10. An inner liner of the container includes five serially connected panels 78, 80, 82, 84 and 86 with the end panels 78 and 86 forming an abutting joint. The panels 10, 68 and 80 have substantially similar dimensions in that their height and width is substantially the same; the panels 10, 68 and 80 can be made to have slightly decreasing widths to allow for the telescoped structure. Similarly, the panels 12, 70 and 82 have substantially similar dimensions, the panels 14, 72 and 84 have substantially similar dimensions, and the panels 16 and 74 have substantially similar dimensions. The panels 86 and 78 when abutted have a combined height and

width which is substantially the same as the height and width of the panels 74 and 16.

The outer box and the liners are preferably made of a corrugated paperboard or cardboard having at least one corrugated layer sandwiched between flat layers. Paperboard having a plurality of corrugated layers sandwiched between flat layers can be employed with equal success. For example, in FIG. 3, the outer box is made of paperboard having a single corrugated layer sandwiched between two flat layers, and the intermediate and inner liners are made of paperboard having two corrugated layers sandwiched between three flat layers.

The inner liner and the intermediate liner are glued together, as indicated by the stippling, so that the panels 78 and 86 of the inner liner secure the joint between the panels 68 and 74 of the intermediate liner. The panel 74 of the intermediate liner joins the panels 78 and 86 of the inner liner.

A tear tape including portions 92 and 94 is secured around the inner circumference of the outer box longitudinally along the panels 10, 12, 14, 16 and 18. The tear tape portions 92 and 94 determine respective tear strip portions of the outer box extending in opposite directions from tabs 90 and 96 a predetermined distance below the top of the container. Conveniently, the tear tapes 92 and 94 are formed from a continuous length of strand reinforced pressure sensitive adhesive tape applied to the inside of the paperboard blank forming the outer box, the tape being severed into the portions 92 and 94 when the tabs 90 and 96 are punched into the blank. The intermediate liner is secured to the outer box by glue as indicated by the stippling only below the tear tape portions 92 and 94 to allow the upper portion of the outer box to be separated from the lower portion of the outer box and form a top for the container which telescopes over the intermediate and inner liners.

It is particularly advantageous that both the intermediate liner and the inner liner form abutting joints, i.e., seams without any substantial separation of the abutting edges of the panels. Thus, when the tear tapes 92 and 94 and the overlying portions of the outer box are ripped, the external surface of the intermediate liner panels 68, 70, 72 and 74 forms a smooth surface for allowing the top portion of the outer box to be telescopically removed and reassembled. Overlapping joints in liners of the prior art present short overlapping sections which interfere with the reassembling of telescoping top portions on the containers.

Similarly, the absence of an interior overlapping panel extending into the interior of the container allows the contents of the container to be more easily removed. For example, a straight edge of a scoop can be engaged with the full length of the interior surface of each side of the container allowing the scoop to readily pick up bulk material in the container; prior art overlapping panels form an additional corner in the interior impeding the engagement of a straight edge of a scoop with a portion of the interior side wall.

Having the overlapping panel 18, the overlapping panel 78 and the junction between the panels 68 and 74 in the same corner allows blanks of the outer box, the intermediate liner and the inner liner to be assembled and glued together in a flat position. Thereafter, the assembled blanks of the outer box, the intermediate liner and the inner liner are folded along score lines between the panels; the panel 78 is glued to the panel 74,

and the panel 18 is glued to the panel 10 to form a manufacturer's joint.

The employment of a long tear tape portion 92 which extends from the tab 90 along panels 10, 12, 14, 16 and 18, in that order, allows the tear strip portion overlying the tape portion 92 to be removed by ripping the tab 90 and the tear tape portion 92 from around the container. During the ripping of the tape portion 92 from the panel 18, force is applied to the panel 18 initially adjacent the hinge line with panel 16 avoiding initial force on the free vertical edge of the panel 18 which would tend to pull the panel 18 from the glued junction with the panel 10. Also, the ripping force is generally applied in the direction of the overlap of the panel 18.

A modified container, shown in FIG. 4, has parts identified by the same reference numerals used to identify parts of the container shown in FIGS. 1-3 to indicate that such similarly identified parts have substantially similar functions and/or structure. The modified box has an inner liner formed from four serially hinged panels 102, 104, 106 and 108, and has an intermediate liner formed from five serially hinged panels 112, 114, 116, 118 and 120. The intermediate liner has the panels 120 and 112 which abut and jointly extend coextensively with the inner liner panel 102 and the outer liner panel 14 while the panels 102 and 108 form an abutting corner joint. The overlapping panel 120 and the joint between the panels 102 and 108 are in the corner diagonally opposite to the manufacturer's joint between panels 18 and 10. The inner liner is glued to the intermediate liner and a lower portion of the outer box below a tear strip is glued to a lower portion of the intermediate liner in the same manner as the embodiment in FIGS. 1, 2 and 3.

Since many changes in detail, variations, or modifications can be made to the present embodiments, it is intended that all subject matter in the description or shown in the accompanying drawings be interpreted as illustrative and not in a limiting sense.

What is claimed is:

1. A laminated container comprising an outer box having five serially hinged side panels, a bottom, and a top, one of said outer box side panels being on one end of the series of outer box side panels for overlapping the outer box side panel on the other end of the series of outer box side panels to form a joint, said outer box side panels having a tear strip extending longitudinally along the series of outer box side panels a predetermined distance below the top for separating a top portion of the outer box from a lower portion of the outer box; an intermediate liner; and an inner liner; one of said intermediate liner and said inner liner having four serially hinged panels, the ends of the series of one liner panels forming an abutting corner joint without any substantial separation of the abutting ends of the series of one liner panels; the other of said intermediate liner and said inner liner having five serially hinged panels, the end panels of the series of other liner panels having a combined size corresponding to a respective one of the panels of said one liner and forming an abutting side joint without any substantial separation of the abutting ends of the series of other liner panels; said outer box side panels, said intermediate liner panels and said inner liner panels forming respec-

tive plies of the sides of the container with the inner liner panels glued to respective intermediate liner panels and lower portions of the intermediate liner panels glued to the respective lower portions of the outer box side panels.

2. A laminated container comprising
an outer box having five serially hinged side panels, 10
a bottom, and a top, one of said outer box side panels being on one end of the series of outer box side panels for overlapping the outer box side panel on the other end of the series of outer box side panels to form a joint, said outer box side panels having a 15
tear strip extending longitudinally along the series of outer box side panels a predetermined distance below the top for separating a top portion of the outer box from a lower portion of the outer box;
an intermediate liner; and
an inner liner;
said intermediate liner having four serially hinged panels, the ends of the series of intermediate liner 20
panels capable of forming an abutting corner joint; said inner liner having five serially hinged panels, the end panels of the series of inner liner panels having a combined size corresponding to a respective one of the panels of said intermediate liner for forming an abutting side joint;
said abutting corner joint of the intermediate liner being in the corner where the joint is formed in the outer box;
said abutting side joint of the inner liner being in a 30
side extending from the corner where the joint is formed in the outer box; and
said outer box side panels, said intermediate liner panels and said inner liner panels forming respective plies of the sides of the container with the inner liner panels glued to respective intermediate liner panels and lower portions of the intermediate liner panels glued to the respective lower portions of the outer box side panels.
3. A laminated container comprising
an outer box having five serially hinged side panels, 40
a bottom, and a top, one of said outer box side panels being on one end of the series of outer box side panels for overlapping the outer box side panel on the other end of the series of outer box side panels to form a joint, said outer box side panels having a 45
tear strip extending longitudinally along the series of outer box side panels a predetermined distance below the top for separating a top portion of the outer box from a lower portion of the outer box;
an intermediate liner; and
an inner liner;
said inner liner having four serially hinged panels, the 50
ends of the series of inner liner panels capable of forming an abutting corner joint;
said intermediate liner having five serially hinged panels, the end panels of the series of intermediate liner 55
panels having a combined size corresponding to a respective one of the panels of said inner liner for forming an abutting side joint;
said abutting corner joint of the inner liner being in the corner diagonally opposite to the corner of the joint formed in the outer box;
said abutting side joint of the intermediate liner being 60
in a side extending from the corner diagonally opposite to the corner of the joint formed in the outer box; and

said outer box side panels, said intermediate liner panels and said inner liner panels forming respective plies of the sides of the container with the inner liner panels glued to respective intermediate liner panels and lower portions of the intermediate liner panels glued to the respective lower portions of the outer box side panels.

4. A laminated container as claimed in claim 1
wherein the tear strip includes
an adhesive tear tape attached to an interior surface 10
of the outer box side panels.
5. A laminated container comprising
an outer box having five serially hinged side panels, 15
a bottom, and a top, one of said outer box side panels being on one end of the series of outer box side panels for overlapping the outer box side panel on the other end of the series of outer box side panels to form a joint, said outer box side panels having a tear strip extending longitudinally along the series of outer box side panels a predetermined distance below the top for separating a top portion of the outer box from a lower portion of the outer box;
an intermediate liner; and
an inner liner;
one of said intermediate liner and said inner liner 20
having four serially hinged panels, the ends of the series of one liner panels capable of forming an abutting corner joint;
the other of said intermediate liner and said inner liner having five serially hinged panels, the end panels of the series of other liner panels having a combined size corresponding to a respective one of the panels of said one liner for forming an abutting side joint;
said outer box side panels, said intermediate liner panels and said inner liner panels forming respective plies of the sides of the container with the inner liner panels glued to respective intermediate liner panels and lower portions of the intermediate liner panels glued to the respective lower portions of the outer box side panels; and
said tear strip including a pair of tabs formed in one of the outer box side panels spaced from the corners thereof for forming two separate portions of the tear strip running in opposite directions.
6. A laminated container as claimed in claim 5
wherein one of the portions of the tear strip is substantially longer than the other portion of the tear strip with the shorter portion of the tear strip being entirely in the outer box side panel on the other end of the series of outer box side panels.
7. A laminated container as claimed in claim 6
wherein the bottom of the box is a bellows bottom including
first and second rectangular panels hinged to respective first and second opposing side panels of the outer box;
first and second triangular panels hinged to respective third and fourth opposing side panels of the outer box;
a third triangular panel hinged at first and second score lines to the respective first rectangular panel and first triangular panel,
a fourth triangular panel hinged at third and fourth score lines to the respective first rectangular panel and second triangular panel,

a fifth triangular panel hinged at fifth and sixth score lines to the respective second rectangular panel and first triangular panel, and a sixth triangular panel hinged at seventh and eighth score lines to the respective second rectangular panel and second triangular panel.

8. A laminated container as claimed in claim 1 wherein

the outer box, the intermediate liner, and the inner liner are made of corrugated paperboard.

9. A laminated container as claimed in claim 8 wherein

the outer box is made of a corrugated paperboard having a single corrugated layer sandwiched between two flat layers, and

the intermediate liner and the inner liner are made of a corrugated paperboard having two corrugated

5

10

15

layers sandwiched between three flat layers.

10. A laminated container as claimed in claim 1 wherein

the abutting corner joint of the one liner is in the corner where the joint is formed in the outer box, and the abutting side joint of the other liner is in a side extending from the corner where the joint is formed in the outer box.

11. A laminated container as claimed in claim 1 wherein

the abutting corner joint of the one liner is in the corner diagonally opposite to the corner of the joint formed in the outer box, and the abutting side joint of the other liner is in a side extending from the corner diagonally opposite to the corner of the joint formed in the outer box.
